UNITED STATES PATENT OFFICE.

LOUIS BOLLMANN AND JOSEF BOLLMANN, OF PENZING, NEAR VIENNA,
AUSTRIA, ASSIGNORS TO GEORGE WOOD RICHARDSON AND ALEXANDER
STORER, BOTH OF LINWOOD, ENGLAND.

OVERSEAM SEWING-MACHINE.

SPECIFICATION forming part of Letters Patent No. 248,552, dated October 18, 1881.

Application filed June 23, 1880. (No model.) Patented in England August 11, 1879.

To all whom it may concern:

Be it known that we, LOUIS BOLLMANN and JOSEF BOLLMANN, of Penzing, near Vienna, Austria, have invented certain new and useful 5 Improvements in Sewing-Machines, (for which we have obtained a patent in Great Britain, No. 3,326, bearing date August 11, 1879,) of which the following is a specification.

The invention relates to means of effecting 10 that kind of sewing which is known as "overhead sewing," the stitches being worked over the edge of the fabric, or of the two or more pieces of fabric that have to be sewed together, as at the edges of sacks and in the seams of 15 gloves. The overhead stitch is, according to this invention, effected by the combined action of three instruments—a shuttle which moves horizontally in a continuous circular path under the fabric, a peculiar needle which moves 20 up and down through the fabric, and a hook which has three sets of reciprocating movements, longitudinally, laterally, and vertically above and over the edge of the fabric. The 25 peculiarity of the needle is that instead of a closed eye it has a hook like that of a crochet-needle near its point, and is fitted with a slide, which at certain times leaves the hook open, so that the thread can be withdrawn from it, and at other times close the gap of the hook, 30 so that the thread is retained as in the eye of a needle. The vertical reciprocating movements of the needle and the three sets of reciprocating movements of the hook are communicated by levers and rods from four suitably-shaped cams on a continuously-revolving horizontal shaft under the table of the machine. The same shaft, by miter-gearing, drives a vertical shaft, which gives motion to the shuttle-driver. The slide which closes the eye of the 35 needle is worked by a small spring-lever mounted on the needle-arm, arranged in such manner that by the movement of the arm it is brought against fixed stops, causing the required movements of the slide to open and close the needle-eye. Above the table of the machine is a bracket carrying a spring-presser of ordinary construction, and in the table is a four-motion feed, also of ordinary construction, worked by 40 cams on the horizontal shaft.

The operation of the machine in effecting the 50 overhead stitch is as follows: The needle, being in its lowest position, has its eye open, having engaged therein a loop of the shuttle-thread. As it rises the eye is closed by the spring acting on the slide of the needle, and the needle 55 carries up through the fabric the loop of thread. The hook seizes this loop, extends it outward beyond the edge of the fabric, and then brings it again inward under the edge of the fabric while the needle descends. The shuttle passes 60 through the thread-loop, and the eye of the needle being now opened, the loop is cast off it and a fresh loop is engaged in its eye; also, the hook, having its loop cast off, reascends, whereupon the operation is repeated, the fabric being fed onward. The successive stitches thus formed are tightened up partly by the action of the needle and hook, but principally by a variable tension and take-up action in the 65 shuttle, which contains the spool of thread. 70 The thread passes from the spool through a hole, across which moves a wedge-shaped pin. At certain points of the revolution of the shuttle this pin is moved, so as to release the thread, by a spring-lever, which revolves with the shuttle round a stationary cam. At other parts of the revolution the pin is moved so as to wedge 75 the thread tightly in the hole, the tension being thus varied.

For a take-up the thread is carried partly 80 round the periphery of a small pulley mounted in the shuttle. This pulley is worked by a clutch from a vertical axis in the shuttle-driver, the clutch being so formed as to permit passage through it of the thread-loop, through 85 which the shuttle passes. On this vertical axis is a pinion gearing with a toothed segment on a lever, which is carried along with the shuttle-driver round a stationary arm so shaped as at certain parts of each revolution 90 to cause the winding up of the thread on the take-up pulley and its unwinding therefrom. The shuttle is of rectangular section, shaped with its front end sharp to enter the thread-loop, swelling out toward and beyond the 95 middle of its length to hold the take-up pulley and spool, and tapering again to its back end or tail, which extends sufficiently far to hold

the thread-loop on it for somewhat more than a quarter of a revolution. The shuttle is driven in its circular path by several upright pins standing up from the revolving shuttle-driver and entering recesses in the under side of the shuttle. These pins are capable of sliding up and down in the driver, and at their lower ends they have T-heads, which travel through a cam-groove on the shuttle-race, so shaped that each of the driver-pins is successively drawn downward, to allow the thread-loop to pass clear between its top and the under side of the shuttle. To prevent the shuttle from being raised out of the race the latter has projecting inward from its cylindrical periphery a circular lip, which enters a groove formed in the exterior surface of the shuttle.

The framing of the machine is mounted on trunnions, so that it can be turned up to examine, cleanse, or repair the mechanism under the table.

Figure 1 is a plan view, partly in section, of a machine constructed in accordance with our invention. Fig. 2 is a vertical longitudinal section of Fig. 1. Fig. 3 is a plan view of the under side of the machine. Fig. 4 is a front elevation of the feed mechanism. Fig. 5 shows a top view of the same. Fig. 6 is a section taken through the casing containing the shuttle and shuttle-driving devices. Fig. 7 is a top view of part of Fig. 6 with the shuttle removed. Fig. 8 is a top view of the shuttle with its cover removed. Fig. 9 is a sectional view of the shuttle on line xx , Fig. 8. Fig. 10 is a view of a lever belonging to the shuttle. Fig. 11 is an edge view of Fig. 10. Fig. 12 is an enlarged view of one end of Fig. 10. Figs. 13, 14, 15, 16, and 17 are views illustrating the device for opening and closing the eye of the needle. Fig. 18 shows two views of the needle. Fig. 19 is a diagram showing different positions of the shuttle. Figs. 20, 21, 22, 23, 24, and 25 are views of the presser-plate and the hook that engages the thread in its different positions. Figs. 26, 27, 28, and 29 illustrate the form of stitch.

In all the figures similar reference-letters are employed to indicate corresponding parts.

The table or main frame of the machine is conveniently made in two pieces, A V, secured together by bolts a , and in order to give ready access to the parts below it may be mounted on a stand by trunnions B B, so that it can be turned up as on hinges.

In bearings below the table is mounted the revolving shaft b , which may be driven, by a belt or otherwise, from any suitable motor. On this shaft are fixed a series of cams, C C' C² C³ C⁴ C⁵, and a miter-wheel, c , by which motion is imparted to the various parts.

On the table A is fixed a bracket, D, carrying the sliding presser-rod d , which is pressed downward by a spring, and can be raised and held up by a lever, E, as in other sewing-machines. The presser-plate e is made of sufficient length and breadth to hold the fabric firmly

under it, and it is fixed to the presser-rod by means of a set-screw, F. The presser-plate e is notched at its right edge to give passage for the needle through it, and at the side of the needle-aperture the notch is made with a nose-like projection, which bears a part in the formation of the stitch, as shown in Fig. 19, and as will hereinafter be explained.

f is the needle-plate, which is sunk into and secured in the table. It is slotted for the passage through it of the serrated feed-plate G, and it is notched, as at H, for the passage of the needle, the notch being made with a nose-like projection, as shown in part plan, Fig. 5. The feed-plate G works flat against the vertical face of the table A within guide-pieces g , one of which is shown in Fig. 4, which represents an elevation of the feed mechanism. A spring, h , draws the feed-slide downward against the cam C⁴, and a spring, I, draws the same laterally against a roller, i , on one arm of a lever, K, a roller on the other arm of which bears against the cam C⁵. By means of the cams C⁴ and C⁵ and the springs h and I the feed receives its four motions, as in other sewing-machines—upward, forward, downward, and backward—these motions being, by the setting of the cams on the shaft b , properly timed to the other movements of the machinery. As the feeding mechanism above described forms no essential part of this invention, it may be constructed and arranged in any other known and suitable manner.

L is the needle-arm, in the form of a bell-crank lever, on a spindle, l , pivoted on the center screws, M M. One arm of this lever has a roller, m , (shown in dotted lines, Fig. 2, and in full lines, Fig. 3,) engaged in the curved path of the barrel-cam C, which gives it reciprocating motion. The other arm carries the needle N, which is curved, and is made with an open eye, somewhat like the hook of a crochet-needle, as shown in Fig. 18.

For the purpose of automatically closing the hook while the needle passes through the fabric and opening it so that when clear of the fabric it can receive and release a loop of the thread, there is employed certain mechanism, which is shown separately in Figs. 13 to 18, inclusive, the mechanism being, however, unnecessary when leather or other non-fibrous material is operated on, in which case the needle-hook might always remain open. This mechanism referred to is as follows:

In the needle-holder is fitted a sliding piece, n , held by screws passing through slots O, which permit of its up and down movement. This sliding piece has its upper end formed as a pin, which works in a groove in the side of the needle N, and which, when slid up relatively to the needle, closes the eye thereof, and when slid down leaves the eye open as a hook, a spring, o , tending to keep the piece n up and the eye closed. The sliding piece n has rack-teeth engaging with teeth on the arm of a bent lever, P, which is pivoted on the needle-arm L,

and whose other arm, with roller *p*, when free, allows the sliding piece *n* to be thrust upward, closing the needle-eye. There are, however, fixed to the table stops *Q*, (shown in Fig. 2,) so placed that when, by the stroke of the needle-arm *L*, the needle-hook is raised above the fabric or brought down below it by the part 1 of the lever *P* coming against the stop in the upstroke of the needle, and by the part 2 of the lever *P* coming against the other stop in the downstroke of the needle, the lever *P* in both cases is moved in opposition to the spring, so as to draw the pin end of the slide *n* downward, leaving the needle-hook open.

15 *R* is the thread-hook, which has a blunt end, and on the side opposite to the hook a short barb. This hook is fixed on an arm, *r*, which is double-jointed at *S* to one arm of a lever, *s*, the opposite arm of which carries a roller engaged in the groove of the barrel-cam *C'*, from which the hook *R* receives a longitudinal reciprocating movement. The arm *r* is connected by the rod *T* by a ball jointed at one end to one arm, *t*, of a bell-crank lever above the table, the other arm, *t'*, of which, below the table, has a roller engaged in the groove of the barrel-cam *C'*, whence the hook *R* receives a reciprocating lateral movement. The arm *r* is also connected by a rod, *U*, ball-jointed at one end to one arm of a bell-crank lever, *u*, the other arm of which bell-crank lever has a roller engaged in the groove of the barrel-cam *C'*, whereby the hook *R* receives a reciprocating vertical movement. The three reciprocating movements of the hook perform functions in the formation of the stitch which will hereinafter be explained. It will be understood that these connecting-rods *T* and *U* have ball-joints at both of their ends.

20 The shuttle-race is formed in a cylindrical hollow part, *V*, of the table, the bottom of the hollow having a bottom plate, *v*, secured by screws. Part of the side of the hollow is open to give space for the working of the needle and hook and of the feed.

25 In a recess in the hollow portion of the table is fitted a ring, *W*, (see Fig. 2,) having an inwardly-projecting lip, which, entering a chase in the lower exterior edge of the shuttle, prevents the shuttle from rising or descending while it revolves.

30 In the center of the shuttle-race is mounted the vertical spindle *A'* of the shuttle-driver *A*², supported at its lower end in a bracket projecting down from the table, which bracket also has a bearing for the end of the shaft *b*. The spindle *A'* passes through a stationary sleeve, on which is fixed a cam, *B'*. There is also a stationary cam-path, *A*³, formed in the bottom of the cylindrical hollow of the table.

35 The shuttle-driver *A*² is worked by the miter-gears *c* and *B*². The manner in which the shuttle-driver *A*² imparts motion to the shuttle *D'*, so as to permit passage of the shuttle through a loop of thread, is shown in Fig. 6. A number of pins, *e'*, having feet *E'*, are fitted

to slide vertically in holes in the shuttle-driver *A*². The upper ends of these pins project above the surface of the shuttle-race and enter recesses in the under side of the shuttle *D'*, so that as these pins are carried round with the driver *A*² the shuttle is necessarily carried round with it also. The lower ends or feet, *E'*, of the pins bearing upon the plate *v* are thereby kept up, engaging with the shuttle during the greater part of their revolution, but at one part thereof they are caused to move down along a cam-path, *E*², formed under a piece, *F'*, whereby the upper ends of the pins are thus successively withdrawn from the recesses in the bottom of the shuttle, thus permitting the passage of the thread-loop under the shuttle. As only one or two of the pins are withdrawn at a time the others that remain engaged with the shuttle maintain its continuous motion.

40 About the middle of the shuttle, in the line *x x*, is a cylindrical recess for the reception of a flat ball or spool of thread, and the whole shuttle is covered by a plate in which are the thread-holes. The front point of the shuttle is so formed as to readily enter a thread-loop, and its back end tapers to a point, being extended sufficiently far to hold the loop till the stitch is tightened.

45 For the proper formation of the stitch, as will be hereinafter explained, it is necessary to provide in the shuttle means for retarding or holding the thread by a drag, so as to give it the necessary tension and permit of its free delivery from the ball or bobbin only at certain times, and also means for taking up slack at certain times.

50 The drag mechanism will be understood by reference to Figs. 1 and 8, and to Figs. 9, 10, 11, and 12, which show certain details of it. The thread from the interior of the ball is threaded downward through a short tube, *G'*, and then threaded upward through a hole, *G*², in a lug, *H'*, projecting from the side of the ball or spool cavity. When a spool is used instead of a ball the short tube *G'* is unnecessary, and the position of the hole *G*² will be modified. A small lever, *H*², is acted on at one end by an adjustable spring, *I'*, so that its other end bears against a stop, *I*². The thread, on its way from tube *G'* to hole *G*², passes between the ends of *H*² and the side of *I*², both of which are on the under side of the shuttle, and it is thus subjected to a drag, giving a tension which may be varied, as desired by the adjustment of the spring *I'*.

55 In the lug *H'* there is a slot, in which a wedge-ended rod, *K'*, can work to and fro, its inclined edge bearing against a pin fixed in the lug, and its opposite edge bearing against the thread passing through the hole *G*². The end *K*² of the rod *K'* has a gab receiving one arm of a bell-crank lever, *L*, which is acted on by a spring, *L*², so as to draw the rod *K'*, causing its wedge end to pinch the thread at *G*², and so prevent its delivery. At a certain part

of each revolution, when the thread has to be delivered, this pinch is relieved in the following manner:

On the shuttle-driver A² (see Fig. 1) is mounted a lever, M', one end of which has a roller traveling round the stationary cam B', its other end bearing against the head of a rod, M², which is urged by a spring, N', under compression. The end of the rod M² bears against the long arm of the lever L'. (See Fig. 8.) Thus at the time that the roller of the lever M' is passing the full part of the cam B' the rod M² and the long arm of L' are pushed in opposition to the spring L², and the wedge part of the rod K' being thus thrust backward, the thread passing through the hole G² is relieved from the pinch and can be freely delivered. The rod M² is shown in Fig. 1 as having its end thrust into the body of the shuttle, being then acted on by the full part of the cam B'. This cam is so formed, however, that throughout the greater part of a revolution the rod M² is withdrawn by its spring N' from the shuttle, thus permitting free passage of the shuttle through the loop of the thread.

The take-up of slack thread is effected as follows: A small reel, O', is mounted on a vertical axis in the shuttle that is fixed to a disk, O², which is below the reel and immediately above another disk, P', fixed on a vertical axis, P², which is mounted in the shuttle-driver A². The faces of the two disks are formed with hollows and projections, so that they clutch each other, the reel O' being thus caused to revolve when the axis P² revolves; but these hollows and projections are so rounded that the thread can freely pass between the two disks. On the axis P² is fixed a toothed pinion, P³, gearing with a toothed segment on one arm, Q', of a lever, the other arm, Q², of which has a roller engaged in the sunk stationary cam-path A³. As the lever Q' Q² is mounted in the shuttle-driver A² it is caused by the travel of its roller in the cam-path A³ to oscillate, and thus by the gearing of Q' with P³ to impart to the axis P² and to the reel O' a reciprocating rotary motion in each revolution of the shuttle. The thread from the hole G² is threaded downward through a hole, R², (shown in Fig. 1,) over the center of the reel O', and thence through a hole, S', (see Fig. 2,) in the rim of the reel, and then up again through a hole, S², in the shuttle-cover, whence it passes to the fabric. Thus as the reel O' is caused, as above described, to revolve backward and forward during the revolution of the shuttle, the slack of the thread is drawn up by it or let out, as determined by the form of the cam-path A³, by which the rotation of the reel O' is governed. The action of the apparatus in forming stitches is illustrated diagrammatically by Figs. 19 to 25, inclusive, and the character of the stitching produced is shown by the plans Figs. 26 and 27, and the sections Figs. 28 and 29. In Fig. 19 the shuttle is indicated in three dif-

ferent positions, 1 2 3, the hook being shown in its attitude corresponding to the position 3 of the shuttle. Assuming stitches to have been already formed, the thread coming out of the last stitch-hole above the fabric has been brought round the nose-like projection of the notch in the presser-plate and down past the edge of the fabric and under it to the shuttle, and the needle has brought down through the fabric a loop, which is entered by the point of 75 the shuttle in its position 3. The shuttle moves onward to 1, the loop being drawn tight by its motion and by the action of the take-up, and at the same time the fabric being fed onward, so that the last stitch-hole is removed from 80 above the needle. The shuttle-thread lying now as indicated in Fig. 20, and the serrated feed having descended, the hook, having also descended, moves, as indicated by the arrow, under the needle-plate and above the serrated 85 feed-plate. It then moves sidewise, as indicated in Fig. 21, and catches the thread below the fabric. It then retreats, as indicated in Fig. 22, and as the shuttle has meanwhile moved onward to the position 2, the previous stitch 90 is drawn tight; also, the drag on the thread by the wedge-rod K' being relieved, a length of thread is drawn out for the next stitch. The hook now rises to its highest position, as shown in Fig. 2, and also advances, as shown 95 in Fig. 23, over the fabric, and the needle rising through the fabric enters the hollow of the hook, throwing out of it the thread-loop, which is now caught by the barb of the hook, so that the needle enters the loop. The hook 100 now performs a small circular movement round the needle, as indicated by the arrow in Fig. 24, causing the loop to engage in the eye of the needle, which is at this time open. The hook, re-engaging the loop of thread, then 105 moves as indicated by the arrow in Fig. 25, and begins its descent. The needle also descends, drawing the loop which it holds down through the stitch-hole. The needle-eye opens and the shuttle enters the loop, which is held by a 110 point of the ring W, where it is cut at the side of the needle. The hook now returns to the position indicated in Fig. 19, and the cycle of operations is repeated, producing a series of 115 overhead stitches, as shown in Figs. 26 to 29, inclusive. The linking together of the loops shown in Fig. 27 may be brought more or less near the stitch-holes by a more or less rapid take-up.

It is obvious that many of the constructive 120 details herein described, and shown in the drawings, might be varied without departing from the essence of the invention.

Having thus described our invention, what we claim is—

1. The combination, with a shuttle arranged to move continuously in an annular path and a hooked reciprocating needle, of devices for carrying the thread from one side of the fabric over the edge thereof and placing it in the 130

hook of said needle on the other side of said fabric, substantially as described, and for the purpose set forth.

2. The combination, with the shuttle traveling in an annular path and the hooked or open-eyed reciprocating needle, of the hook R, and devices for moving the same laterally under and over the fabric and vertically past the edge thereof, substantially as and for the purpose set forth.

3. The combination, with the shuttle having tube G' and hole G², of the stationary cam B', lever M', spring-rod M², spring-lever H², bar K', and bell-crank lever L', substantially as described.

4. The combination, with the reel O', mounted on the shuttle, of suitable devices actuated automatically for causing a reciprocating rotary movement of said reel, substantially as and for the purpose set forth.

5. The combination, with the reel O', mounted in the shuttle and having an axis or spindle provided with disk O², of the disk P', interlocked with said disk O², and carried by a spindle or axis, P², provided with a toothed pinion, P³, the lever-arm Q', pivoted to the shuttle-driver and provided with a toothed segment meshing with said pinion, and devices for automatically vibrating said arm, substantially as described.

In testimony whereof we have signed our names to this specification, in the presence of two subscribing witnesses, this 1st day of June, A. D. 1880.

LOUIS BOLLMANN.
JOSEF BOLLMANN.
